UNITED STATES PATENT OFFICE.

WILLIAM STROBRIDGE, OF RIVERTON, NEW JERSEY, ASSIGNEE TO UNITED STATES
CAST IRON PIPE & FOUNDRY COMPANY, OF BURLINGTON, NEW JERSEY, A COR-
PORATION OF NEW JERSEY.

APPARATUS FOR APPLYING SKILLY TO CORE-BARS.

1,305,675.

Specification of Letters Patent. Patented June 3, 1919.

Application filed October 10, 1916. Serial No. 124,805.

To all whom it may concern:

Be it known that I, WILLIAM STROBRIDGE, a citizen of the United States, and a resident of Riverton, in the county of Burlington and State of New Jersey, have invented a certain new and useful Improvement in Apparatus for Applying Skilly to Core-Bars, of which the following is a true and exact description, reference being had to the accompanying drawings, which form a part thereof.

My present invention consists in an improved means for forming pipe mold cores comprising metallic core bars coated first with skilly and then with loam, or the like. The purpose of the skilly layer interposed between the metallic core bar proper and the loam coating is to provide a layer which will be readily frangible after being heated, as it is in the poured mold; so that it may be readily broken up in the core bar withdrawal operation and thereby facilitate the longitudinal movement of the core bar out of the molded pipe.

The material known as skilly is applied to the core bar in a fluid or paint like condition and is thoroughly dried before the loam coating is applied. The skilly coating becomes exceedingly fragile and readily breaks up, practically in a powdered condition, after being heated to the temperature to which it is subjected when the molds are poured. The composition of the material known as skilly may vary considerable in practice but its general nature will be made clear by the following example of a satisfactory mixture; namely, one in which the non-liquid ingredients of the skilly consists of between twenty and thirty parts of each of the following substances: coke screenings, blacking, peat moss and manure; and between two and three parts of paper and sawdust. To these ingredients sufficient water is added to render the mixture fluid and of a paint like consistency.

The object of the present invention is to provide an improved apparatus for applying skilly to core bars easily, expeditiously uniformly and at a comparatively low labor cost. More specifically the invention has for its object to provide an apparatus for applying skilly to the core bars of a continuously operating pipe molding plant in

such a manner as to efficiently utilize the heat which remains in the core bars at the end of each mold forming operation, in drying and baking the skilly coats, and in drying and baking the loam coats applied to the core bars to fit them for subsequent use. The accomplishment of this enables me to minimize the time and fuel required to fit the core bars for use with the skilly and loam coats properly dried and baked in place.

The gist of my invention is the provision of apparatus whereby the application to the core bars immediately after being drawn from the molds following the pouring of the latter, of a coating of skilly which is sprayed on in such a manner as to secure the desired uniformity of coating and the desired quick drying and baking of the skilly coating. By proceeding in this manner only a relatively small amount of the heat of the core bar is wasted during the skilly application owing to the rapidity of the application and the insulating property of the skilly layer, and the fact that practically every particle of skilly impinging against the core bars adheres to the latter. In consequence, the heat of the core bars not utilized in drying and baking the skilly coatings is conserved and may be utilized in drying and baking the loam coating or coatings applied to the core bars as soon as the skilly coatings on the latter are thoroughly dried and baked.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described a preferred embodiment of my invention.

Of the drawings:

Figure 1 is a somewhat diagrammatic plan view of a portion of a pipe plant comprising apparatus constructed in accordance with the present invention and adapted for use in practising the method forming a part of the present invention;

Fig. 2 is a plan view taken on a larger

scale than Fig. 1, and showing a portion only of the apparatus shown in the last mentioned figure;

Fig. 3 is an end elevation of the apparatus shown in Fig. 2;

Fig. 4 is a partial elevation taken similarly to Fig. 3, but on a larger scale and showing a portion only of the apparatus shown in Fig. 3;

Fig. 5 is a partial elevation taken at right angles to Fig. 4 and showing a portion of the apparatus shown in Fig. 2;

Fig. 6 is an elevation of one of the core lowering bars;

Fig. 7 is an elevation taken at right angles to Fig. 3 of a portion of the apparatus shown in Fig. 2;

Fig. 8 is a somewhat diagrammatic representation of the skilly mixing and spraying apparatus proper; and

Fig. 9 is an elevation of a portion of the spray nozzle.

In the drawings I have illustrated the use of my invention in, and in connection with a pipe founding plant in which pipes are formed in vertical pipe molds A' shown as arranged in circular series mounted on a turn table or other suitable support.

Associated with the mold supports are two sets of instrumentalities each comprising a core bar receiving table B; a core bar rotating device C; storing provisions D for the skilly coated core bars; a loam applying lathe or striker E and core cars F running on tracks G into heating ovens H.

In operation the core bars L are drawn from the molds A' within a few minutes after the molds have been poured ordinarily by suitable overhead crane mechanism not shown, and are deposited on one or the other of the tables B. In practice, and with the parts proportioned as indicated in the drawings, the core bars may advantageously be drawn from the molds in sets of twelve each, though it is to be understood that the twelve core bars of each set need not be simultaneously drawn from the molds. The core bars of each set are deposited on one of the tables B, successive sets of core bars being deposited alternately on the two tables B. From each table B a set of core bars deposited thereon at one time are run off on to the adjacent core bar rotating machine C. The latter as shown is formed in two sections C' and C² which are duplicates of one another except in one respect hereinafter referred to. Each of the sections C' and C² comprises a pair of parallel end supports C³ and C⁴. Each end support C³ is provided with bearings for a plurality of short parallel shafts C⁶. Each of the shafts C⁶ carries at one end a roll C⁵ which may well be knurled, and at the other end a gear wheel C⁷ in mesh with a worm shaft C⁸ which extends lengthwise of the support C³ and

meshes with all of the gear wheels C⁷ mounted therein. C⁹ C¹⁰ represent cranks by means of which and the shafts C⁸ the various rolls C⁵ are rotated. Each support C⁴ has journaled on it a plurality of rolls C¹⁰ which are co-axial each with a corresponding one of the rolls C⁵ and are of the same diameter as the latter roll. As shown, each roll C¹⁰ is journaled on a stationary shaft C¹¹ secured in the support C⁴. The rolls C⁵ and C¹⁰ are spaced such a distance apart that the group of core bars L supported thereby will be spaced apart from one another as shown best in Figs. 2 and 3.

Journaled in the supports C³ and C⁴ of each section C² are a pair of short shafts J' which are parallel to, and below the level of the shafts C⁶ and C¹¹. The supports C³ and C⁴ of the section C' each have journaled in them one short shaft J' and are each provided with bearings for a single long shaft J² which is thus journaled in the two end supports. Secured to each of the shafts J is a corresponding arm J and similar arms J are secured to the shaft J² adjacent the supports C³ and C⁴. Each of the arms J has its free end pivotally connected to a bifurcated arm I' depending from a bar I which extends transversely to the shafts J' and J². There are two of the bars I, one lying alongside and approximately equal in length to the combined length of the two supports C³, and the other of the same length and lying alongside of two supports C⁴. Each bar I lies alongside the corresponding rolls C⁵ or C¹⁰ and is adjustable between a core bar receiving position in which its upper edge is above the level of the upper edges of the rolls C⁵ and C¹⁰, and a second position in which its upper edge is below the lower edges of core bars resting on the rolls C⁵ and C¹⁰. The bars I are raised and lowered by rotating the long shaft J². The latter is extended beyond the support C³ and provided with a crank arm J³ in which is swiveled a nut J⁴ receiving a threaded shaft J⁵ which is swiveled in a support J⁶ in which the shaft J² is journaled. The screw shaft J⁵ is rotated by means including a crank J⁷ and the bars I correspondingly raised and lowered.

In placing core bars on the core bar rotating device C, the bars I are raised above the level of the upper sides of the rolls C⁵ and C¹⁰, after which the core bars are rolled on to the bars I from the table B. After the core bars are thus mounted on the rolls or bars I and are properly spaced thereon, the bars I are lowered by manipulating the crank J⁷ to let the core bars down into engagement with the corresponding rollers C⁵ and C¹⁰. In this condition of the apparatus the core bars mounted on each of the sections C' and C² may be simultaneously rotated by revolving the corresponding crank C⁹.

With the core bars mounted on the core rotating devices C as described, the skilly is applied to the core bars in the form of a spray, being sprayed in succession on different portions of the surface of the bars being roated, and the sprayed sections being given an opportunity to dry sufficiently to "set" the skilly before the bars are rotated and other sections thereof sprayed. C¹⁵ represents a removable board or plate mounted in each core bar rotating device C to prevent any portion of the skilly spray directed against the core bars mounted in one of the sections C' and C² from falling on bars mounted in the other of said sections.

The skilly spraying apparatus in the form illustrated comprises a skilly mixing reservoir M which may advantageously, as shown, be located below the floor level and is in the form of a horizontal tank containing a rotating mixer or stirring device M' driven by suitable means as a motor M¹⁰. M² represents a filling connection provided with a removable cap M³ located above the floor level. M⁴ represents a valved vent pipe connected to the upper side of the reservoir M, and N' represents a pressure reducing valve through which compressed air is supplied to the reservoir M from a compressed air supply pipe N when the latter is in operation. M⁵ and M⁶ represent delivery pipes running from the lower portion of the reservoir M to points adjacent the two devices C where, as shown, they are provided with cut off valves M⁷ and are each adapted to be connected to a hose or flexible spray pipe P. The air supply pipe has extension N² and N³ terminating adjacent the valved ends of the pipes M⁵ and M⁶ and provided with cut off valves N⁴ and adapted to be connected thereby, each to a flexible pipe or hose which with the corresponding hose or pipe O runs to the spraying device Q proper. The latter, in the form shown, comprises a chambered body which, as shown, comprises two tubular sections connected by a chamber Q² of larger cross section. To the outer end of one of the tubular sections the hose pipe O is connected, and the outer end of the other tubular section terminates in the discharge nozzle Q'. Preferably as shown, the nozzle G' is formed by flattening the end of the corresponding tubular section of the body, and advantageously, also, by giving it the concave end edge shown. I have found that a spray nozzle formed in this manner effectively delivers a uniform and concentrated spray jet; that is, one in which the opposite sides of the fan like discharge make a comparatively small angle with one another as follows: In the chamber Q² is located an air jet nozzle Q³ to which the air supply hose is connected. The nozzle Q³ discharges an axial jet directly toward the spray nozzle outlet Q'. O' and P' are regulating valves

through which the pipes O and P respectively are connected to the body Q. N' is a cut off valve in the compressed air supply pipe N.

A preferred general mode of using the apparatus disclosed consists in drawing core bars from the previously poured molds practically as soon after pouring as is possible, and depositing the core bars in sets of a dozen each alternately on the two receiving tables B. From each receiving table B the set of core bars deposited thereon are rolled on to the corresponding core bar rotating device C. At the time the bars are rolled on to the rotating device C the rails I are in their elevated position and the board, or dividing plate C¹⁵, is removed. The core bars which are run on to the rails I are so disposed on the latter, either initially or as they are lowered, that when the rails I are fully lowered, each core bar will be supported at one end by two rolls C⁵ and at the other end by the corresponding pair of rolls C¹⁰. The rails I of each device are lowered by manipulating the corresponding crank J². After the core bars are thus dropped on the supporting rolls C⁵ and C¹⁰, the partition plate C¹⁵ is put back into place and the core bars are then sprayed with the skilly by a workman who holds the sprayer Q and directs the spray jet in the proper direction. The spraying operation is carried out in successive sections or stages. In the first stage of the spraying operation, the upper sides of the group of core bars mounted on one section, as for instance, section C' of one of the core bar rotating devices, are sprayed, and then the upper sides of the group of core bars on the other sections (C²) of the same core bar rotating device are sprayed. Then the core bars of the group first acted on are given a partial turn by the manipulation of the corresponding crank C⁹, after which the then uppermost sides of the core bars of this group are sprayed with skilly. This stage is followed by a corresponding rotation of the bars of the other group and the spraying of their then uppermost sides, and so on until both groups of core bars are completely coated with skilly.

I have found that by thus dividing the spraying operations to which each group of core bars is subjected, into a suitable number of stages, it is possible to coat the bars with skilly in a very uniform and satisfactory manner. By causing the spray jet to travel back and forth over the core bar surfaces to be coated during each spraying operation it is possible to spray the exposed portions of each group of core bars in a couple of minutes or so without applying the spray to any one portion of any bar rapidly enough to prevent the skilly from adhering as it impinges sufficiently to avoid objectionable running or splashing of the

skillfully. Ordinarily I prefer to spray each group of core bars in three stages giving the bars a third of a turn between successive spraying operations. By proceeding in the manner described, and allowing a sufficient time interval which will be approximately equal to that required for performing one spraying operation on another group of core bars to elapse between the successive stages of the operation of spraying a single group of core bars, no difficulty will ordinarily be experienced from the skillfully running on the partially coated bars when the latter are given the partial turn needed to put them in position for a succeeding spraying operation. Ordinarily a single coating of skillfully applied in the manner described is sufficient as with the means and mode of operation described a single coating of three-eighths of an inch or so in thickness can readily be applied. It is readily possible, however, to apply two or more coats of skillfully in successive spraying stages when this seems necessary or desirable.

25 After the spraying operation for each group of core bars is completed and sufficient time has elapsed for the skillfully last applied to set, the core bars are passed to the storage stack D. As shown, the core bars are here arranged in superimposed tiers the core bars in each tier being mounted in a corresponding set of notched bars receiving the uncoated ends of the core bars supported thereby and resting on the uncoated portions of the subjacent core bars. From the stack D the core bars are taken one at a time to the core lathe E and given the first coating of loam after which they are placed on core ears F and pushed into the drying ovens H. After the first coat on each core bar is dried, the core bar is returned to the lathe and given a second coat of loam and is then coated with blacking after which the bar is put back on the core ear and again pushed into the oven to complete the drying, after which the core bar is ready to be again inserted in the mold.

By proceeding in accordance with the present invention it is possible to coat the core bars while they are still hot enough to quickly and thoroughly dry the skillfully, this operation requiring a temperature of about 400° F. In the normal operation of a continuously operating plant mold, the core bars which are insulated to some extent against heat radiation by the skillfully coatings will pass through the storage stack and core lathe E while still hot enough so that the drying of the first loam coat will be materially aided by the heat still retained in the core bar. The heat retained in the core bars when the latter with the skillfully and first loam coats are put into the drying ovens H reduces the amount of heat which it is necessary for the core bars to absorb from the

ovens and consequently reduces the time and fuel required for the loam drying operation.

While in accordance with the provisions of the statutes I have illustrated and described the best embodiment of my invention now known to me, it will be obvious to those skilled in the art that changes may be made in the form of the apparatus disclosed and in the mode of practising the invention described, without departing from the spirit of the invention. It will also be apparent to those skilled in the art that some features of the invention may sometimes be used with advantage without a corresponding use of other features.

Having now described my invention, what I claim as new and desire to secure by Letters Patent, is:—

1. Apparatus for coating core bars with skillfully comprising in combination means for supporting two groups of parallel closely spaced horizontally disposed core bars, and means for intermittently rotating each group independently of the other.

2. Apparatus for coating core bars with skillfully comprising in combination means for supporting two groups of parallel closely spaced horizontally disposed core bars, means for intermittently rotating each group independently of the other, and means for discharging skillfully in the form of a spray on the exposed upper sides of the core bars.

3. Apparatus for coating core bars with skillfully comprising in combination a core bar support provided with means for supporting a plurality of closely spaced core bars, means for intermittently imparting a partial rotation to the various bars mounted on said support and skillfully spraying apparatus comprising a skillfully reservoir, means for agitating the contents thereof, and a pneumatic sprayer for withdrawing skillfully from said reservoir and discharging it in a spray on the exposed upper sides of the core bars.

4. Core bar supporting and rotating means comprising in combination two sets of devices for rotatably supporting the opposite ends of core bars arranged side by side, and means located between said sets of devices and movable from one position in which they are adapted to support said core bars and hold them out of engagement with said devices into another position in which they permit the core bars to be engaged and supported by said devices.

5. A core bar supporting and rotating mechanism comprising in combination two spaced apart sets of rollers for rotatably supporting the opposite ends of a group of parallel core bars, and guide rails extending transversely to the axes of said rollers and lying between the two sets of rollers and movable from one position in which their upper edges are above the upper sides of

said rollers into another position in which they clear the under sides of core bars supported by said rollers.

6. A core bar supporting and rotating device comprising in combination means for supporting a plurality of parallel core bars arranged side by side in two closely spaced

groups, means for intermittently rotating the bars in each group independently of the other group and a removable barrier for preventing a spray jet of skilly directed against one group from impinging against the other group.

WILLIAM STROBRIDGE.
